UNITED STATES PATENT OFFICE.

WILLIAM WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SHED-FORMING MECHANISM FOR LOOMS.

SPECIFICATION forming part of Letters Patent No. 752,316, dated February 16, 1904.

Application filed December 17, 1903. Serial No. 185,479. (No model.)

To all whom it may concern:

Be it known that I, WILLIAM WATTIE, a citizen of the United States, residing at Worcester, in the county of Worcester and State of Massachusetts, have invented certain new and useful Improvements in Shed-Forming Mechanism for Looms, of which the following is a specification.

My invention relates to shed-forming mechanism for looms, and more particularly to a harness-motion in which two harnesses are used, ordinarily termed a "two-harness motion." One harness is raised when the other is lowered, and vice versa.

The object of my invention is to improve upon the ordinary construction of the shed-forming mechanism in the class of looms referred to and to provide a strong and efficient mechanism to positively raise and lower the harnesses and raise the back harness higher than the front harness and cause a dwell of the harnesses in their upper and lower positions when the shuttle passes through the shed.

My invention consists in certain novel features of construction of my improvements, as will be hereinafter described.

I have only shown in the drawings sufficient parts of a loom with my improvements thereon to enable those skilled in the art to which my invention belongs to understand the construction and operation of the same.

Referring to the drawings, Figure 1 is a central vertical section through the loom and a harness-motion embodying my improvements, taken at a point indicated by line 1 1, Fig. 2, looking in the direction of arrow *a*, same figure. Fig. 2 is a sectional front view of the parts shown in Fig. 1, taken at a point indicated by line 2 2, Fig. 1, looking in the direction of arrow *b*, same figure. Some of the parts shown in Fig. 1 are not shown in this figure. Fig. 3 is a central vertical section through a loom and a harness-motion, taken at a point indicated by line 3 3, Fig. 4, looking in the direction of arrow *c*, same figure, and showing a modified construction of my improvements. Fig. 4 is a sectional front view of the parts shown in Fig. 3, taken at a

point indicated by line 4 4, Fig. 3, looking in the direction of arrow *d*, same figure. Some 50 of the parts shown in Fig. 3 are not shown in this figure. Fig. 5 shows, on an enlarged scale, a detached portion of the pinion-and-rack mechanism; and Fig. 6 shows a modified construction of the pinion-and-rack mechanism 55 shown in Fig. 5.

In the accompanying drawings, Figs. 1 and 2, the loom sides or frames 1, the arch 2, the lay 3, the connection from the lay 3 to the crank-shaft 4, which is geared to the bottom or cam shaft 5, as indicated by broken lines in Fig. 1, the let-off roll 6, and the take-up roll 7 are all of the ordinary and well-known construction in looms having a two-harness motion.

I will now describe my improvements which 65 relate particularly to the harness-motion. A rock-shaft 8 is mounted above the two harnesses 9 and 10 in suitable bearings 11' on brackets 11, secured to the arch 2. A second rock-shaft 12 is mounted below the two harnesses 9 and 10 in suitable bearings 13 on the loom sides 1. Fast on the rock-shaft 8 are two pairs of pulleys 14 and 15. One pair, as 14, is of larger diameter than the other pair, and each pulley 14 has one end of a strap or flexible 75 band 16 secured thereto to be wound and unwound thereon as the shaft 8 rotates first in one direction and then in the other. The other end of the straps 16 is in this instance attached to one end of an adjustable connector or link 17, 80 and the other end of the connector 17 is attached to the upper edge of the back harness 9. The other pair of pulleys, 15, fast on the rock-shaft 8, are of a little less diameter than the pulleys 14, and each pulley 15 has one end 85 of a strap or flexible band 19 secured thereto to be wound and unwound thereon as the shaft 8 rotates. The other end of the strap 19 is in this instance attached to one end of an adjustable connector or link 20, and the other end of the connector 20 is attached to the upper edge of the front harness 10. On the rock-shaft 12 below the two harnesses 9 and 10 are also fast 90 two pairs of pulleys 14' and 15' of similar diameter to the pulleys 14 and 15, respectively, 95 each pair connected by straps or flexible bands

16' and 19' through connectors or links 17' and 20' to the lower edges of the harnesses 9 and 10 in the same manner as the straps 16 and 19. The larger diameter of the pulleys 14 and 14' 5 on the rock-shafts 8 and 12 will cause the rear harness 9 to be raised higher and to be lowered more than the front harness 10.

I will now describe the mechanism shown in Figs. 1 and 2 for simultaneously rotating the shafts 8 and 12 first in one direction and then in the other to positively raise and lower the two harnesses 9 and 10 and cause a dwell of the harnesses in their two extreme positions. On the upper rock-shaft 8, near the 15 ends thereof, are fast two pinions 21, and fast on the lower rock-shaft 12, near the ends thereof and in vertical line with the pinions 21, are fast two pinions 22. Two vertically-moving parallel rods 23 have secured to their upper 20 ends a rack 24, each of which meshes with a pinion 21, fast on the rock-shaft 8, and is held in engagement therewith by a strap 25, secured to the rack 24 and extending back of and engaging the shaft 8, as shown in Fig. 1. Attached to the lower ends of the vertically-moving rods 23 are two racks 26, each of which 25 engages with a pinion 22, fast on the lower rock-shaft 12, and is held in engagement therewith by a strap 27, secured to the rack 26 and extending back of and engaging the shaft 12, as shown in Fig. 1. A vertical motion is communicated in this instance simultaneously to each of the vertically-moving rods 23 (to communicate, through racks 24 and 26 and pinions 30 21 and 22, a simultaneous rocking motion to the shafts 8 and 12 to cause, through pulleys 14 and 15 and 14' and 15' and strap connections to the harnesses 9 and 10, a positive raising and lowering of the harnesses) by a cam 35 28, fast on the bottom shaft 5, having in this instance a cam-groove 28' in one face thereof, into which extends and travels a roll 29' on a lever 29, pivoted at one end on a stud 30 on a bracket 31, secured to the loom side 1, and pivotally connected at its other end to a link 32. The other end of said link 32 is pivotally connected with a projection 23' on the vertically-moving rod 23.

It will be understood that there is a cam 28 40 and intermediate mechanism for each vertically-moving rod 23. (See Fig. 2.)

The shape of the cam 28 is such that when the harnesses 9 and 10 are in their extreme 45 positions there is a dwell of the harnesses while the shuttle passes through the shed.

I have shown in Figs. 3 to 6, inclusive, a modified construction of the mechanism for operating the vertically-moving rack-rods which through intermediate connections operate the 50 harnesses. In said figures I have lettered similar parts with the same letters used in Figs. 1 and 2.

I will now describe the modified construction of the operating mechanism shown in 55 Figs. 3 to 6, inclusive. The lay 3, as shown

in Fig. 3, is operated from the bottom shaft 5. A pinion 33, eccentric to the bottom shaft 5 and fastened thereon, meshes with and drives an elliptic gear 34, fast on the end of a shaft 35, mounted in bearings 36' on a stand 36. (See Fig. 4.) Fast on the other end of the shaft 35 is an arm 37, pivotally connected by a pin 38 with one end of a link 39. The other end of the link 39 is pivotally connected to an ear 40' on the vertically-moving rack-bar 40. (See Fig. 4.) The vertically-moving rack-bar 40 has a rack or teeth on its upper and lower ends, which engage the pinions 21 and 22, fast on the rock-shafts 8 and 12, to raise and lower the harnesses 9 and 10, as above described in 80 connection with Figs. 1 and 2. The racks on the rack-bar 40 are held in engagement with their pinions by grooved rolls 41, located back of and in engagement with the rear edge of the rack-bar 40, as shown in Fig. 3 and also 85 in Fig. 5.

It will be seen that by means of the pinion 33 and the elliptic gear 34 an intermittent rotary motion of the shafts 8 and 12 is obtained to cause a dwell of the harnesses in their extreme positions while the shuttle is passing through the shed.

In Fig. 6 is shown a modified construction of the mechanism for obtaining a dwell of the harnesses. In said figure the rock-shaft 8 has 95 an elliptic gear 42 mounted thereon, which engages with the teeth on one edge of the vertically-moving rack-bar 43 to be operated thereby. On the opposite edge of the rack-bar 43 are a second set of teeth, which are engaged by the teeth on a second elliptic gear 44, loose on a stud 45.

The rotation of the elliptic gear 42 will at regular intervals cause a dwell in the rotation of the rock-shaft 8 and also a dwell in the 105 movement of the harnesses. The second elliptic gear 44 acts to hold the gear 42 in mesh with the rack-bar 43.

The revolution of the elliptic gear 42 by the rack-bar 43 causes a dwell of the harnesses in 110 their extreme positions, when the shuttle is thrown through the shed.

It will be understood that the details of construction of my improvements may be varied, if desired, and the same are adapted to be applied to any looms of well-known construction and operation to positively raise and lower the harnesses in the manner above described.

Having thus described my invention, what I claim as new, and desire to secure by Letters Patent, is—

1. In the shedding motion of a loom, the combination with two harnesses, a rock-shaft above, and a rock-shaft below the harnesses, two pairs of pulleys on each rock-shaft, connections between said harnesses and said pulleys, of means for simultaneously rotating both shafts, first in one direction and then in the other, said means consisting of a vertically-moving bar having rack-teeth thereon to en- 125 130

gage a pinion on each shaft, and said pinions, and means for operating said bar, substantially as shown and described.

2. In the shedding motion of a loom, the combination with two harnesses, a rock-shaft above, and a rock-shaft below the harnesses, two pairs of pulleys on each rock-shaft, one pair of greater diameter than the other, flexible connections attached to said pulleys, and adjustable connections intermediate said flexible connections and the harnesses, of means for simultaneously rotating both shafts, first in one direction and then in the other, to raise and lower the harnesses, said means consisting of a vertically-moving bar having rack-teeth to engage a pinion fast on each rock-shaft, and said pinions, and means for holding the racks in contact therewith, and means for intermittently operating said bar, to cause a dwell of the harnesses in their two extreme positions, substantially as shown and described.

3. In the shedding motion of a loom, the combination with two harnesses, a rock-shaft above, and a rock-shaft below the harnesses, two pairs of pulleys on each rock-shaft, one pair of greater diameter than the other, flexible connections attached to said pulleys, and adjustable connections intermediate said flexible connections and the harnesses, of means

for simultaneously rotating both shafts, first in one direction and then in the other, to raise and lower the harnesses, said means consisting of a vertically-moving bar having rack-teeth to engage a pinion fast on each rock-shaft, and said pinions, and means for holding the racks in contact therewith, and means for intermittently operating said bar, to cause a dwell of the harnesses in their two extreme positions, substantially as shown and described.

4. In the shedding motion of a loom, the combination with two harnesses, a rock-shaft above, and a rock-shaft below the harnesses, two pairs of pulleys on each rock-shaft, connections between said pulleys and the harnesses, of means for communicating a simultaneous intermittent rotary motion to both rock-shafts, first in one direction and then in the other, to raise and lower the harnesses, said means consisting of a vertically-moving bar having rack-teeth thereon to engage a pinion or gear on each rock-shaft, and said pinions or gears, and means for operating said bar, substantially as shown and described.

WILLIAM WATTIE.
